PRESSURIZED DISPENSING CONTAINER

Louis V. Nigro, Saugus, Mass., assignor to The Gillette
Company, Boston, Mass., a corporation of Delaware

Filed July 9, 1969, Ser. No. 18,128

Term of patent 14 years

Int. Cl. D9—01

U.S. Cl. D9—9

Fig. 1.

Fig. 2.

Fig. 3.

Fig. 4.

Fig. 5.

Fig. 6.

Fig. 7.

Fig. 8.

Fig. 9.

Fig. 10.

Fig. 11.

Fig. 12.

Fig. 13.

Fig. 14.

FIG. 1 is a perspective view of a pressurized dispensing container showing my new design;

FIG. 2 is a front elevational view thereof;

FIG. 3 is a back elevational view thereof;

FIG. 4 is a side elevational view thereof;

FIG. 5 is a top plan view thereof; and

FIG. 6 is a bottom plan view thereof. The undisclosed side is a mirror image of the side shown.

FIG. 7 is a perspective view of another embodiment of my new design;

FIG. 8 is a front elevational view thereof;

FIG. 9 is a back elevational view thereof; and

FIG. 10 is a side elevational view thereof. The undisclosed side is a mirror image of the side shown. The undisclosed top is substantially the same in appearance as that shown in FIG. 5. The undisclosed bottom is substantially the same in appearance as that shown in FIG. 6.

FIG. 11 is a perspective view of still another embodiment of my new design;

FIG. 12 is a front elevational view thereof;

FIG. 13 is a back elevational view thereof; and

FIG. 14 is a side elevational view thereof. The undisclosed side is a mirror image of the side shown. The undisclosed top is substantially the same in appearance as that shown in FIG. 5. The undisclosed bottom is substantially the same in appearance as that shown in FIG. 6.

I claim:

The ornamental design for a pressurized dispensing container, substantially as shown and described.
